[57] CLAIM

The ornamental design for a dual-chambered hydro tub
spa, as shown and described.

DESCRIPTION

FIG. 1 is a top plan view of a dual-chambered hydro tub
spa, showing my new design;

FIG. 2 is a side elevational view thereof;

FIG. 3 is a right side elevational view thereof;

FIG. 4 is a top perspective view thereof;

FIG. 5 is a bottom plan view thereof; and

FIG. 6 is a cross-sectional view taken along line 6—6 of
FIG. 1.

FIG. 1

FIG. 2

FIG. 3

FIG. 4

FIG. 5

FIG. 6
